COLLAPSIBLE TABLE

William B. King, Leaksville, N. C.

Application December 26, 1933, Serial No. 704,017

5 Claims. (Cl. 311—83)

My invention relates to collapsible tables for use as card tables, tea tables, etc., and it consists in the combinations, constructions and arrangements herein described and claimed.

5 One of the objections to the use of the ordinary collapsible card table having legs at the corners is that this precludes the provision of a hinged ash tray at this point. The corner of the table is the most convenient position for the ash tray 10 as far as the players are concerned, since an ash tray at a corner will be out of the way of the knees of the players and give access to players on two sides of the table.

When the table is used as a tea table, or when 15 there is an extra player at the card table as there may be for some card games, a table with a leg at each corner is objectionable because the corner leg interferes with the knees of the player or guest where the table is used as a tea table.

20 An object of my invention is to provide a folding table with the legs so disposed that hinged ash trays can be placed at the corner underneath the table top where they may be readily moved into position for use.

25 A further object of the invention is to provide a table of the type described in which the legs are positioned inwardly so as to give plenty of knee room all around the table, thus permitting the use by more than four without inconvenience.

30 A further object is to provide a novel means of securing the legs so as to provide a stable construction when the legs are in open position for use, while at the same time permitting them to be folded into parallelism with the top so as to 35 make the table compact and providing for convenient storage.

Other objects and advantages will appear in the following specification and the novel features of the invention will be particularly pointed out 40 in the appended claims.

My invention is illustrated in the accompanying drawings forming part of this application, in which:

Figure 1 is a perspective view of a table constructed according to my invention.

Figure 2 is an enlarged section on the line 2—2 of Fig. 1.

Figure 3 is a bottom plan view of the device in its folded position.

50 Figure 4 is a sectional view on the line 4—4 of Fig. 2, and,

Figure 5 is a sectional view on the line 5—5 of Fig. 3.

In carrying out my invention I provide a table 55 top 6, preferably of wood, and having an outer

covering or surface 7 of mahogany or other finishing material. The top 6 is preferably provided with integral laterally extending flanges 6^a, which have cut away portions 6^b, serving as ornamental features and also providing additional knee room. The flanges 6^a are braced to the top by means of triangular shaped blocks 8 so as to provide a 5 strong construction.

Extending from side to side and parallel with the side flanges are strips 9, these strips having 10 similar triangular shaped braces 8. Each of these strips 9 has a longitudinally extending groove 10, the purpose of which will be explained later. Parallel with the strips 9 and spaced apart from them are smaller guide strips 11, which 15 extend from one side, but terminate short of the other, as shown in Fig. 1.

Two pairs of legs are provided, an inner pair 12 curved as shown in the drawings, and an outer pair 13 curved to conform to the curvature 20 of the inner pair and pivoted to the inner pair by pivot screws 14. The legs 12 of the inner pair are joined together near their central portions by means of a flat member 15 which is shaped as shown in Fig. 1, and also by a cross 25 member 15^a at their tops. The outer pair of legs 13 are connected together by a flat member 16 on one side and by a member 17 on the opposite side shown in dotted lines in Fig. 1.

The outer legs 13, as will be seen from Fig. 4, 30 are secured to blocks 18 which are rounded at their tops to permit the pivotal movement of the legs, and these legs are pivoted at 19 to slidable blocks 20. As will be seen from Fig. 4 each of these blocks 20 has a tongue arranged 35 to enter the groove 10 of the strip 9 on one side, and has a cut away portion arranged to receive the guide strip 11 on the opposite side. The blocks 20 are each provided with a spring pressed locking pin 21 arranged to enter an opening 40 in its respective strip 9.

Secured to the bottom of the top 6 is a block 23 having a plate or strip 24 secured thereto and projecting beyond the inner face thereof as shown in Fig. 2. This block is braced by triangular 45 braces 8 similar to those already described, and is provided with a pivoted latch member 25.

From the foregoing description of the various parts of the device, the operation thereof may be readily understood. Figure 3 shows the table in 50 collapsed position. In this position the latch member 25 keeps the legs in their folded position. When it is desired to use the table, the latch member 25 is turned to clear the inner leg 12. Both pairs of legs are then swung on 55

the pivots 19, and the legs together with their attached blocks 20, are pushed inwardly toward the center of the table, that is to say, from left to right in Fig. 3. When the spring actuated pins reach the openings 22 they will enter these openings, thus locking the legs in position. The inner legs 12 are then move on their pivots 14 until the strips 15x engage the block 23, see Fig. 2. In this position the member 24 will enter underneath the bar or strip 15x so as to hold the legs in their open position when the table rests on the legs in the position shown in Fig. 2.

15 Ash tray holders, such as those shown at 26, may be pivoted at 27 at the corners, these holders being provided with openings arranged to engage ash trays (not shown).

Flexible members 28 may be attached between the legs 12 and 13 below the pivot 14 to prevent undue extension of the legs.

20 A device constructed as described is stable, easily collapsed or set up, can accommodate more than four persons, for instance at afternoon teas, and can hold ash trays at the corners in the most convenient position for the persons grouped at 25 the table.

I claim:

1. In a collapsible table, a top member, guide means secured to said member, slideable blocks carried by said guide means, a pair of legs rigidly secured together and pivoted between said blocks, a second pair of legs rigidly connected together and pivotally connected to the first pair, said second pair of legs being normally disconnected from said top member, and means for automatically locking said blocks to said guide means when said blocks have reached a predetermined position.

2. In a collapsible table, a top member, guide means secured to said top member, slideable blocks carried by said guide means, a pair of legs rigidly secured together and pivoted between said blocks, a second pair of legs normally disconnected from said top member, a cross member rigidly connecting said second pair of legs together, means for pivotally mounting the second pair of legs on the first pair, and a retaining member secured to the underside of the table

and having a projecting flange arranged to underlie said cross member for limiting the pivotal movement of said second pair of legs with respect to the first pair.

3. In a collapsible table, a top member, guide means secured to said top member, slideable blocks carried by said guide means, a pair of legs rigidly secured together and pivoted between said blocks, a second pair of legs, a cross member connecting said second pair of legs together, means for pivotally mounting the second pair of legs on the first pair, a retaining member secured to the underside of the table and having a projecting flange arranged to underlie said cross member for limiting the pivotal movement of said second pair of legs with respect to the first pair, and automatic means for locking the guide blocks to their respective guides when said blocks have moved to a predetermined position.

4. In a collapsible table, a top member, guide means secured to the underside of said top member, a pair of blocks carried by said guide means and slideable thereon, certain of said guide means having an opening, a spring-pressed pin carried by each of said blocks and adapted to enter its respective opening in its guide member when the pins are in registration therewith, a pair of legs rigidly secured together and pivoted between said blocks, and a second pair of legs rigidly secured together and pivotally connected to the first pair.

5. In a collapsible table, a top member, guide means secured to the underside of said table member, a pair of blocks carried by said guide means and slideable thereon, certain of said guide means having an opening, a spring-pressed pin carried by each of said blocks and adapted to enter its respective opening in its guide member when the pins are in registration therewith, a pair of legs rigidly secured together and pivoted between said blocks, a second pair of legs rigidly secured together and pivotally connected to the first pair, and a retaining means secured to the underside of the table for limiting the pivotal movement of the second pair of legs with respect to the first pair.

WILLIAM B. KING.
